US0D1013812S

(12) **United States Design Patent** (10) **Patent No.:** **US D1,013,812 S**
(45) **Date of Patent:** ** *Feb. 6, 2024

(54) **DOMED AND DIMPLED GOLF BALL MARKER**

(71) Applicant: **ON POINT BALL MARKER LLC**, Basalt, CO (US)

(72) Inventors: **Briston Peterson**, Basalt, CO (US); **James Joseph Verna**, Basalt, CO (US)

(73) Assignee: **ON POINT BALL MARKER LLC**, Basalt, CO (US)

(*) Notice: This patent is subject to a terminal disclaimer.

(**) Term: **15 Years**

(21) Appl. No.: **29/791,612**

(22) Filed: **Jan. 21, 2022**

Related U.S. Application Data

(63) Continuation of application No. 29/740,638, filed on Jul. 6, 2020, now Pat. No. Des. 956,157, which is a continuation of application No. 29/672,877, filed on Dec. 10, 2018, now Pat. No. Des. 889,580, which is a continuation-in-part of application No. 29/655,568, filed on Jul. 5, 2018, now Pat. No. Des. 872,817.

(57) **CLAIM**

The ornamental design for a domed and dimpled golf ball marker, as shown and described.

DESCRIPTION

FIG. 1 is a perspective view of a domed and dimpled golf ball marker in accordance with the new design;

FIG. 2 is an exploded bottom perspective view thereof;

FIG. 3 is a top plan view thereof;

FIG. 4 is a bottom plan view thereof;

FIG. 5 is a side elevational view thereof; and,

FIG. 6 is a side elevational view thereof.

The broken lines in FIGS. 1-6 illustrate portions of the domed and dimpled golf ball marker that form no part of the claimed design.

1 Claim, 6 Drawing Sheets
